Fig. 4.

UNITED STATES PATENT OFFICE.

SOPHIA C. HULL, OF SPRAGUEVILLE, NEW YORK.

TAG.

No. 911,306.

Specification of Letters Patent.

Patented Feb. 2, 1909.

Application filed March 23, 1908. Serial No. 422,745.

To all whom it may concern:

Be it known that I, SOPHIA C. HULL, a citizen of the United States, residing at Spragueville, in the county of St. Lawrence and State of New York, have invented a new and useful Tag, of which the following is a specification.

This invention relates to tags or markers and has for its object to provide a comparatively simple and inexpensive device of this character especially designed for attachment to a bee-hive for displaying the number of the hive.

A further object of the invention is to provide a tag or marker including a casing having a holder slidably mounted therein and adapted to receive a card bearing the number of the hive, said holder being provided with means for supporting a memorandum slip.

A still further object of the invention is generally to improve this class of devices so as to increase their utility, durability and efficiency.

Further objects and advantages will appear in the following description, it being understood that various changes in form, proportions and minor details of construction may be resorted to within the scope of the appended claims.

In the accompanying drawings forming a part of this specification: Figure 1 is a plan view of a tag or marker constructed in accordance with my invention. Fig. 2 is a transverse sectional view taken on the line A—B of Fig. 1. Fig. 3 is a perspective view of the casing. Fig. 4 is a similar view of the slide or holder detached from the casing. Fig. 5 is a detail perspective view of one end of the slide or holder looking at the rear face thereof.

Similar numerals of reference indicate corresponding parts in all of the figures of the drawings.

The improved tag or marker comprises a casing or housing 5 preferably stamped or otherwise formed from a single piece of metal, the opposite longitudinal edges of which are bent laterally and inwardly to form parallel guide flanges 6 adapted to receive a slide or holder.

The opposite ends of the casing are offset at 7 and extended longitudinally beyond the flanges 6 to form terminal ears 8 having perforations 9 formed therein for the reception of screws, nails or similar fastening

devices 10 by means of which the case may be secured in position on a bee-hive or other suitable support.

The holder is slidably mounted between the overhanging flanges 6 of the casing and is preferably of a length equal to approximately the length of the flanges 6, there being an angle plate 11 secured to and extending transversely across the case at one of the terminal ears 8 for limiting the longitudinal movement of said holder. The holder is also preferably formed of a single sheet of metal the opposite longitudinal edges of which are bent upwardly and inwardly to form parallel flanges 12 adapted to engage the flanges 6 on the casing, the metal after the flanges 12 are formed being bent upon itself and extended downwardly and laterally beneath and in spaced relation to the base 13 of the holder to form auxiliary flanges or supports 14.

Slidably mounted between the flanges 12 of the holder is a display card 15 upon which may be printed or otherwise represented a number corresponding to the number of the hive, there being a strip of mica, glass or other transparent material 16 interposed between the flanges 12 and the card 15 for protecting the latter against the action of the elements.

The auxiliary flanges 14 rest upon the bottom of the casing 5 and are spaced from the base 13 of the holder a sufficient distance to accommodate one or more memorandum slips or leaves 17 upon which may be printed or written data pertaining to bee-culture or these slips or leaves may be used for keeping dates and other memoranda.

The flanges 12 are provided with longitudinal grooves or depressions 18 adapted to receive the downwardly inclined spring flanges 6 of the case thereby to assist in preventing accidental separation of the parts. Attention is here called to the fact that the flanges 6 frictionally engage the flanges 12 at the depressions 18 so as to effectually prevent the holder from dropping out of the casing during transportation or shipment.

One end of the base 13 of the holder is extended longitudinally beyond the flanges 12 and provided with a terminal finger piece 19 by means of which the holder may be conveniently withdrawn from or positioned within the casing. It will here be noted that the memorandum slips or leaves 17 are

2
interposed between the base 13 of the holder and the bottom of the casing 5 so that said leaves are effectually housed and protected, the card 15 being protected by the transparent strip 16, in the manner before described. It will also be noted that the lower edges of the flanges 12 at the grooves or depressions 18 yieldably engage the transparent strip 16 so as to retain the card in position on the holder, the longitudinal movement of the card and transparent strip being limited by engagement with the finger piece 19 and stop 11.

The tags or markers may be made in different sizes and shapes and while particularly designed for attachment to a bee-hive may be used with equally good results as a shipping tag for boxes, crates and similar receptacles.

20 Having thus described the invention what is claimed is:

1. A tag including a casing, a holder slidably mounted in the casing and adapted to receive a display card on one side thereof, and means disposed on the opposite side of the holder for supporting a memorandum slip.

2. A tag including a casing, a holder slidably mounted in the casing and provided on one side thereof with means for engagement with a display card, means disposed on the opposite side of the holder for supporting a memorandum slip, and a transparent plate covering the display card, said holder and casing being provided with interengaging parts.

3. A tag including a casing having oppositely disposed attaching ears and provided with spaced guide flanges, a holder slidably mounted between the flanges of the casing and provided on one side thereof with means for engagement with a display card, and means disposed on the opposite side of the holder for supporting a memorandum slip.

4. A tag including a casing having parallel guide flanges and provided with oppositely disposed attaching ears, a holder slidably mounted between the flanges and provided on one side thereof with means for engagement with a display card, means disposed on the opposite side of the holder for supporting a memorandum slip, and a stop extending transversely of the casing for limiting the longitudinal movement of the holder.

5. A tag including a casing having spaced longitudinally disposed guide flanges inclined downwardly in the direction of the base of the casing, a holder slidably mounted in the casing and provided with corresponding flanges having depressions formed therein for the reception of the flanges on the casing, means carried by the holder for supporting a memorandum slip, a display card supported on the holder, and a transparent strip interposed between the flanges on the holder and the display card, and held in position on the display card by engagement with the depressed portions of the flanges. 70

6. A tag including a casing having oppositely disposed guide flanges, a holder slidably mounted in the casing and provided with corresponding guide flanges the edges of which are bent laterally beneath the holder to form auxiliary flanges adapted to support a memorandum slip, a display card carried by the holder, and a transparent plate covering the display card.

7. A tag including a casing having longitudinally disposed guide flanges, a holder formed of a single piece of metal, the opposite longitudinal edges of which are bent laterally to produce flanges adapted to engage the flanges on the casing, the metal at 85 the flanges on the holder being extended inwardly in spaced relation to the base of the holder to form an intermediate pocket for the reception of a memorandum slip, a display card carried by the holder, and a transparent plate interposed between the flanges 90 on the holder and said display card.

8. A tag including a casing having longitudinally disposed guide flanges, a holder slidably mounted between said flanges and 95 formed of a single piece of metal, bent to produce longitudinal flanges for engagement with the flanges on the casing, one end of the metal forming the holder being extended longitudinally beyond the adjacent flanges to 100 produce a finger piece, and a stop extending transversely across the casing for limiting the longitudinal movement of the holder in one direction.

In testimony that I claim the foregoing as 105 my own, I have hereto affixed my signature in the presence of two witnesses.

SOPHIA C. HULL.
